Fig. 5

FIGURE 1 is a perspective top view of a closure plug embodying my new design;

FIGURE 2 is a top plan view thereof;

FIGURE 3 is a bottom plan view thereof;

FIGURE 4 is a side elevational view thereof; and

FIGURE 5 is a transverse vertical sectional view, as seen from the plane 5—5 on FIGURE 2.

The design is characterized by a generally elliptically shaped plate set into the well of the cap and having semi-circular dome-like lugs on opposite ends of said plate.

I claim:

The ornamental design for a closure plug, substantially as shown and described.
